UNITED STATES PATENT OFFICE

121,526

DESIGN FOR A SUPPORTING WALL BRACKET

Wendell H. Swartz, Marion, Ind., assignor of one-half to Ross McClain, Marion, Ind.

Application March 30, 1940, Serial No. 91,367

Term of patent 7 years

To all whom it may concern:

Be it known that I, Wendell H. Swartz, a citizen of the United States, residing at Marion, in the county of Grant and State of Indiana, have invented a new, original, and ornamental Design for a Supporting Wall Bracket, of which the following is a specification, reference being had to the accompanying drawing, forming part thereof.

In the drawing: Fig. 1 is a top plan view of a supporting wall bracket, showing my new design; and Fig. 2 is a front elevational view thereof, the back being plain.

I claim:

The ornamental design for a supporting wall bracket, as shown and described.

WENDELL H. SWARTZ.
